UNITED STATES PATENT OFFICE.

ALFRED GREENOUGH MARSH, OF WARNER, NEW HAMPSHIRE, ASSIGNOR
TO THE MERRIMACK GLOVE COMPANY, OF SAME PLACE.

MITTEN.

SPECIFICATION forming part of Letters Patent No. 319,987, dated June 16, 1885.

Application filed March 23, 1885. (No model.)

To all whom it may concern:

Be it known that I, ALFRED GREENOUGH MARSH, of Warner, in the county of Merrimack, of the State of New Hampshire, have 5 invented a new and useful Improvement in Mittens; and I do hereby declare the same to be described in the following specification and represented in the accompanying drawings, of which—

10 Figure 1 is a front view, and Fig. 2 a rear view, of a mitten as made in accordance with my invention, the nature of which is defined in the claim hereinafter presented.

15 The object of my improvement is to enable to be utilized, in the manufacture of leather mittens, what are usually termed "waste pieces" of material, generally too small for a whole back or front to be made from, or too small for the formation of one of the two parts of 20 which the thumb has generally been constructed.

25 In carrying out my invention I compose the back A of the mitten of two longitudinal gore-pieces, *a a*, extending lengthwise of such back, and of a series of intermediate sections or pieces, *b b*, &c., extending from one gore-piece to the other, such intermediate pieces, *b*, being arranged in range with each other, and with their next adjacent edges in contact, and 30 connected by cast-over stitching *c*, running from each to the next one in succession, all the said intermediate pieces at their ends being arranged edge to edge with the gore-pieces and jointed to them by "cast-over" stitching 35 *d*, as represented. The front B of the mitten, except the thumb C, I compose of several pieces, *d e e*, placed edge to edge, and connected by cast-over stitching *f*, the said

front at its longer edges being united by sewing to those of the back. The front of the 40 thumb I usually make of a single piece, and the back of such thumb of two or more pieces sewed together; but the thumb may be formed of its back in one single piece and its front in another. The upper section, *d*, of the front 45 I propose to have in one piece, extending upward from the base or lowest part of the thumb, as represented, all the wrist portion of the front being in one or more sections, *e*, stitched together at their abutting edges. The 50 longitudinal gores serve as stays to prevent the intermediate back pieces or the portions of the front from being torn or pulled apart while the mitten may be in use. Such gores I usually make of leather thinner or more flexible than that of the intermediate pieces or of the front, in order that the hand of a person having the mitten on it may be easily closed, or, in other words, the second, third, fourth, 55 and fifth fingers be turned down with little 60 constraint toward the palm.

I claim—

A mitten having the front provided with a thumb and composed of a single piece of material extending upward from the base of the 65 said thumb, and of one or more wrist portions or pieces extending below the said base, in combination with the back composed of two longitudinal gore-pieces and a series of intermediate sections or pieces, all being arranged and united by sewing, substantially 70 as set forth.

ALFRED GREENOUGH MARSH.
